[57] CLAIM

The ornamental design for a link element as shown and described.

DESCRIPTION

FIG. 1 is a front elevational view of a link element showing my new design;

FIG. 2 is a bottom plan view;

FIG. 3 is a left side elevational view;

FIG. 4 is a vertical sectional view taken along the line 4—4 in FIG. 1;

FIG. 5 is an exploded front elevational view;

FIG. 6 is a perspective view; and

FIG. 7 is a perspective view in an alternate configuration of FIG. 6.

The broken line showing of a circular supporting element in FIGS. 6 and 7 is for illustrative purposes only and forms no part of the claimed design.

FIG. 1

FIG. 3

FIG. 2
